Primary Examiner — Doris Clark(74) *Attorney, Agent, or Firm* — Workman Nydegger**(57) CLAIM**

The ornamental design for a wave ripple panel, as shown and described.

DESCRIPTION

FIG. 1 is a top right perspective view of a wave ripple panel including our design;

FIG. 2 is a front, facing view thereof;

FIG. 3 is an elevated right side view thereof;

FIG. 4 is top plan view thereof; and,

FIG. 5 is a bottom plan view thereof.

The broken lines are included for the purpose of showing environmental portions of the wave ripple panel and form no part of the claimed design.
